(57) **CLAIM**

The ornamental design for a milk creamer/mixer with holder, as shown and described.

DESCRIPTION

FIG. 1 is a perspective view of a milk creamer/mixer with holder showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side view thereof;

FIG. 7 is a right side view thereof; and,

FIG. 8 is an exploded view thereof.

The portions shown in broken lines are included for illustrative purposes only and form no part of the claimed design.
